UNITED STATES PATENT OFFICE.

HENRY L. DOHERTY, OF NEW YORK, N. Y.

PROCESS FOR BURNING POWDERED FUEL.

1,145,356.

Specification of Letters Patent.

Patented July 6, 1915.

Application filed December 31, 1909. Serial No. 535,844.

To all whom it may concern:

Be it known that I, HENRY L. DOHERTY, a citizen of the United States, and a resident of New York city, in the county of New York and State of New York, have invented certain new and useful Improvements in Processes for Burning Powdered Fuel, of which the following is a specification.

10 This invention relates to a process for burning powdered fuel.

The objects of my invention are, firstly, the obviating of the danger of explosion in the fuel feed-pipe conveying the powdered fuel to the furnace, and secondly the regulation of the combustion so that the temperature produced may be controlled to any desired extent, thereby permitting the use of powdered fuel for low temperature operations and avoiding the burning out of furnaces, which latter is a common result of the ordinary methods of firing with powdered fuel.

My invention, briefly stated, consists in 25 the substitution of inert or non-oxidizing gases—such as flue gas—for air, as the vehicle in which the powdered fuel is carried into the furnace, the said flue gas being supplied under pressure and the mixture of 30 flue gas and powdered fuel discharged into the combustion chamber through an appropriate inductor passage, whereby the air necessary for the combustion of the fuel is drawn into the inductor so that the combustion gases are substantially free from significantly reactive amounts of uncombined 35 oxygen. The volume of the flue gas used as the fuel-conveying medium is varied according to the temperature desired in the 40 furnace—or, rather, according to the flame temperature desired. The presence of the flue gas in the flame acts in two ways. In the first place, it retards the velocity of reaction by lowering the partial pressure of 45 the oxygen in the initial combustible mixture, and by its mechanical effect in diluting the oxygen so that an appreciable time is required before the carbon particles come 50 into reactive proximity with sufficient oxygen molecules for their combustion, and in the second place it adds to the combustion mixture a large volume of inert gas whose temperature must be raised by the heat of the reaction as well as that of the normal 55 combustion gases. The first effect causes the combustion to take place with a com-

paratively slow burning dilated flame while the second effect causes a diminution in the normal flame temperature commensurate with the volume of flue gas relative to the 60 air. The precise volume of flue gas used to carry the powdered fuel per pound of the latter will vary according to the temperature desired in the furnace, the nature and quality of the fuel, etc., as well as the 65 quality of the flue gas itself,—i. e. according to the proportion of CO_2 in the latter.

In the usual method of burning powdered fuel it is necessary to use a very large excess of air in order that the flame temperature shall not be sufficiently high to cause fluxing of the furnace walls. This practice produces a flue gas which may contain by volume as much as 14% of free oxygen. Such a gas is not suited for use in my process. I find that by my method of conducting the combustion I am enabled to secure a practically complete combustion with a very small excess of air. With proper regulation and provision against leakage of air 80 into the furnace I find that the volume of flue gas per pound of carbon may advantageously be between 60 and 200 cu. ft. (normal). The former giving a high flame temperature, while with the latter quantity the 85 flame temperature is reduced to about that given by a poor producer gas.

In the accompanying diagrammatic drawings I have shown a form of apparatus capable of applying my process to boiler 90 firing.

Figure 1 shows an arrangement whereby the powdered fuel and flue gas are mixed, while Fig. 2 shows the method of introducing the fuel-current into the furnace of a 95 boiler. Fig. 3 is a part elevation of the front of a single boiler showing the burners, and position of the fuel conduits.

1 indicates a blower whose suction pipe, 2, is connected to some source of flue, or 100 other non-oxidizing gases—in the present case, the main flue of the boiler plant.

3 is the discharge pipe of the blower which is connected to a nozzle-shaped fuel mixer 4.

105 4 is connected to the hood 5 enveloping the discharge end of fuel conveyer 6 by passage 7. A valve, 8, in suction pipe 2 of the blower serves to regulate the volume of flue gas discharged by blower 1. The 110 powdered fuel is fed into 7 by conveyer 6, and is taken into suspension by the current

of flue gas passing through 4. The fuel laden current of flue gas thence passes through the conduit 9, and is distributed to the furnaces.

5 The proportion of flue gas to fuel which I use depends upon the nature of the operation which I wish to carry out; or, in other words, upon the flame temperature which I wish to produce. For boiler firing, it is only necessary to use sufficient flue gas to bring the flame temperature down to about 2700° 65 Fah. In this case, the temperature permissible is limited, chiefly, by the resistance which the fire-brick structure of the boiler 70 furnace offers to the fluxing action of high temperatures. On the other hand, in brick kilns, annealing furnaces, and the like, where a moderate flame temperature is desired, it may be necessary to bring the temperature 75 of the flame as low as 1700° to 1800° Fah. In this case, a much larger proportion of flue gas to fuel is necessary. While I do not restrict myself to any specific proportion of flue gas, as it is manifest that this may 80 be varied to suit the conditions it is desired to obtain, I may say, that for ordinary furnace operations, I use from 60 to 200 cu. ft. of flue gas per lb. of powdered fuel, the minor proportion being used for high 85 temperatures and the major for low flame temperatures.

The fuel laden current of flue gas passes through the main conduit, 9, to the connections 10', 10'', 10''', etc., of the boiler 90 furnaces. In the form of burner figured, 11 is the burner tube, proper, which is composed, preferably, of some highly refractory material such as fire-clay. The fuel-laden current of flue gas is discharged through the 95 nozzle, 12, the volume of the fuel current being regulated by the valve 13. Air for combustion is admitted through damper 14, which may be of any suitable type.

From the arrangement of apparatus 100 shown, it is obvious that the current of flue gas laden with powdered fuel will discharge into the combustion chamber as a truncated conical body surrounded with an envelop of air, which latter is drawn in through the 105 damper 14 and the annular passage of burner 11 surrounding the nozzle 12. The initial combustion therefore takes place over the conical surface of the flue gas body—the fuel-laden flue gas and air gradually mixing as 110 the two currents flow through the combustion chamber, the initial conical annulus of flame gradually changing into a diffused flame with the increase in the distance from the point of introduction. By this method 115 of introducing the powdered fuel separate

from the air, the former is only exposed to oxidizing conditions gradually, although the temperature of the combustion chamber into which it is introduced is far above its ignition temperature. There is thus exerted a 65 retarding effect upon the combustion in addition to that exerted by the presence of the flue gas, and it is possible to prolong the flame to a greater extent, with a given proportion of flue gas, than would be otherwise 70 possible.

Suitable settling chambers (not shown) should be provided either in the flue connections of the individual boilers or at the base of the stack. Suitable cleaning doors 75 should also be provided to give access to the bottom of the furnace chambers and to the flue gas conduits. The flue gas connection from the blower should be made to the flue 80 gas conduits after the settling chambers.

Having described my invention, what I claim is:

1. The method of burning powdered fuel which comprises suspending said powdered fuel in an accelerated draft current of combustion gases, said draft current containing a less proportion of free oxygen than that required to form a combustible mixture with said powdered fuel, and discharging the fuel-laden draft current into a combustion 90 chamber in such manner as to induct air into said chamber as a conical annulus surrounding said fuel-laden draft current the volume of induced air required for the combustion of the fuel carried by the said draft current, 95 whereby the said fuel-laden draft current is caused to mix gradually with said air to produce a prolonged combustion.

2. The method of burning powdered fuel which comprises, suspending the said powdered fuel in a draft current of combustion gases substantially free from a significant excess of uncombined oxygen, introducing the said fuel-laden draft current into a combustion space maintained at an igniting temperature, introducing into said combustion space as a separate draft current sufficient air to burn said powdered fuel, the air current being introduced as an annular gaseous body enveloping said fuel-laden draft current, whereby a slow combustion of said powdered fuel is caused with the production of a prolonged flame.

Signed at New York city in the county of New York and State of New York this 115 30th day of December A. D. 1909.

HENRY L. DOHERTY.
